VARIABLE RATE GEARING FOR VENDING
MACHINES

Théodor Dietrich and Raymond Cuénod, Geneva,
Switzerland, assignors to Landis & Gyr, A.-G.,
Zug, Switzerland, a body corporate of Switzerland

Application July 29, 1939, Serial No. 287,280
In Switzerland August 5, 1938

3 Claims. (Cl. 74—325)

The invention relates to novel and improved mechanism for variable transmission gearing, and more particularly to gearing for varying the rate or duration of operation of mechanisms designed to operate for selected predetermined periods, for example, automatic metering and vending machines designed to deliver electricity, gas, or the like in predetermined amounts for a certain coin or rate.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrates one embodiment of the invention, and together with the description, serves to explain the principles of the invention.

Of the drawing:

Figure 1 is a partially diagrammatic plan view of a mechanism embodying the invention;

Figure 2 is a view similar to Fig. 1 of a modified embodiment; and

Figure 3 is a detail in elevation of a linking member employed in the dual mechanism shown in Fig. 2.

Objects of the invention are to provide an improved and simplified, variable rate gearing for coin-controlled metering or vending apparatus whereby the rate of operation of the apparatus may be varied widely by very simple and inexpensive means. Heretofore in setting such apparatus for operation at different rates with relation to a certain coin, e. g., the ratio between the coin that is dropped into the machine and the consumption of current or the running time of a meter, flat rate motor or clock, it has been necessary to exchange whole sets of gears. This was troublesome and expensive and involved danger of inadvertently displacing measuring elements of the mechanism during manipulation of the gearing. The present invention overcomes these disadvantages, only one gear requiring to be exchanged and that being conveniently located in the most accessible part of the mechanism. Moreover, the danger of derangement of settings during the exchange is overcome as the invention provides for automatically locking the permanent parts of the mechanism during the exchange operation and for automatically releasing

them when the exchanged gear is allocated in its operative relationship.

Referring now in detail to the present preferred embodiment of the invention, illustrated by way of example in the accompanying drawing, a relatively simple form thereof is shown in Figure 1. As embodied, the driving worm 1 is preferably driven by a coin-controlled driving motor and differential gear not shown. The essential parts of the mechanism are supported from a main rear plate 1 and from a parallel spaced plate 2. A permanently positioned step gear 4 having any desired number of pinions of different diameters is mounted at the end of a main shaft 3 on the front side of the plate 2. Shaft 3 is driven at suitable speed from the worm 1 by means of gear 5 which meshes with gearing 6 on the intermediate shaft 6a.

The invention provides a release switch or cam 16 adapted to be rotated at the predetermined rate from the step gear 4 and to release the meter switch or other control means not shown upon reaching the predetermined position in accordance with the rate determined by the coin control or the like. Release member 16 is mounted on the end of shaft 15 to the rear of plate 1, said shaft being driven through gear 14 meshing with gear 11 which is fixed to the intermediate shaft 8. A helical spring 20 is fixed at one end to the control member 16 on shaft 15 and at its other end in the plate 1, whereby the counterforce of the spring causes immediate stoppage of the rotation of shaft 15 upon release of the switch or the like through cam member 16.

In accordance with the invention the driving connections between step gear 4 and the intermediate shaft 8 are designed to permit ready selection of the desired step on gear 4 and during the exchange to automatically lock the remaining parts of the driven mechanism in their proper positions. As embodied, a gear 18 is removably mounted on the portion of shaft 8 which projects in front of plate 2 and is there adapted to engage one of the steps of gear 4. The hub 19 of gear 18 is slotted at its inner end so as to fit about a pin 10 projecting from shaft 8. The outer end of shaft 8 is reduced and threaded to receive the knurled nut 17 which on being tightened presses against the outer end 30 of the hub of gear 18 and thereby causes the hub 19 of said gear to move inwardly along the shaft 8. Shaft 8 is provided with an outwardly projecting sleeve 31 which extends through a suitable opening in plate 2 and at its outer end bears against the inner end of hub 19. An enlarged annular shoulder or brake

disc 12 is provided on the hub 31 adjacent the inner surface of plate 2. Said brake disc 12 is urged toward frictional engagement with the inner surface of plate 2 by a coil spring 13 connecting the fixed gear 11 and the movable brake 12. Brake 12 is normally held out of engagement with plate 2 by compression of the spring 13 through contact between the end of hub 19 and sleeve 31, that is, when gear 18 is seated in position by the screwing down of nut 17. However, when an exchange gear 18 is removed from the mechanism, release of the nut 17 causes brake 12 to immediately engage the surface of plate 2 and thereby restrain further rotation of gear 11 and the remaining members of the train to release member 16. Setting of the exchange gear by screwing down of the nut 17 will release shaft 8 for operation with the new gear.

In Fig. 2 is shown a form of the invention designed for providing a greater range of gear ratios than possible with the form in Fig. 1. As embodied, a dual set of exchange gears driven from the step gear 4 is provided, that is, a second intermediate shaft 8' is mounted parallel to shaft 8. A second exchange gear 24 is mounted for engagement with a different pinion of the step gear 4, while the movable brake 12' actuating spring 13' and other similarly prime numbered parts will be recognized to correspond to the similarly numbered parts of the companion shaft 8. The rotating motion from shaft 8' is coupled to that from shaft 8 through differential gearing 25 mounted on shaft 15. A pinion 21 on shaft 8' drives gear 22 and thereby one side of differential 25, while the opposite side 35 of the differential is driven from gear 34.

The foregoing arrangement makes possible much more extensive gear ratios. For example, if the gear ratios possible through shaft 8 are from 1 to 10, while the gears 21 and 22 drive the differential ten times more rapidly, it is thus possible through the coupling axle 8' to provide gear ratios in steps of tens up to one hundred, i. e., squares of the basic ratio from shaft 8. In this manner with a set of ten exchange gears it is possible to provide gear ratios from one to one hundred in unit steps.

When, in the form of Figure 2, it is desired to utilize only the gear ratios available from the shaft 8, the gear 24 may be disconnected from the coupling axle 8' and the brake 12' will then lock the shaft 8'. In this case the gearing will run only on one sun wheel of the differential 25, transmitting directly the impulse from shaft 8.

Means are provided for preventing loss of the kurled nuts 17 and 17', which may easily happen in exchanging the gears 18 and 24. For this purpose the nuts are connected to a cross link 23 having yoked or fork-shaped openings at its ends which permit free turning of the nuts while 60

preventing them from sliding out of the yokes. Thus when one nut is loosened, it remains hanging on the link and connected to the other nut.

The invention in its broader aspects is not limited to the specific mechanisms shown and described but departures may be made therefrom within the scope of the accompanying claims without departing from the principles of the invention and without sacrificing its chief advantages.

3. What we claim is:

1. Transmission gearing for variable-rate vending machines or the like including in combination a driven member operable at predetermined rates, step gearing for actuating said member at different selective rates, means for interchangeably connecting a preselected exchange gear with a step of said step gearing to vary the rate of operation of said driven member, and means for automatically locking the driven member in position during the interchange of said gear and for restoring the driven member to operative condition upon completion of said interchange, said means including a brake on the exchange gear shaft actuated by axial movement of the exchange gear along said shaft.

2. Transmission gearing for variable-rate vending machines or the like including in combination a driven member operable at predetermined rates, step gearing for actuating said member at different selective rates, means for interchangeably connecting a preselected exchange gear with a step of said step gearing to vary the rate of operation of said driven member, and means for automatically locking the driven member in position during the interchange of said gear, comprising a spring-pressed brake coaxial with the exchange gear adapted to lock the driven member in position and means on the exchange gear for normally holding said brake out of locking engagement.

3. Transmission gearing for variable-rate vending machines or the like including in combination a driven member operable at predetermined rates, step gearing for actuating said driven member at different selective rates, and means for interchangeably connecting a preselected exchange gear with a step of said step gearing to vary the rate of operation of the driven member, means for automatically locking said driven member in position during the interchange of said gear, comprising a brake adapted to lock the driven member in position, said brake comprising a disc on the exchange gear shaft actuated by axial movement of said exchange gear along said shaft, and means for normally holding said brake disc out of braking engagement.

THEODOR DIETRICH,
RAYMOND CUENOD.
